His attorney.

UNITED STATES PATENT OFFICE

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

APPARATUS FOR THE CONTROL OF RAILWAY-CAR RETARDERS

Application filed May 15, 1928, Serial No. 277,838. Renewed January 21, 1930.

My invention relates to apparatus for the control of railway car retarders of the type in which the retarder devices are actuated by fluid pressure.

- 5 One feature of my invention is the provision of means for securing several different pressures in the actuating mechanism with the minimum number of line wires between the retarder and its controlling lever.
- 10 I will describe two forms of apparatus embodying my invention, and will then point out the novel features thereof in claims.

In the accompanying drawing, Fig. 1 is a diagrammatic view showing one form of apparatus embodying my invention. Fig. 2 is a diagrammatic view showing a modification of the apparatus shown in Fig. 1 and also embodying my invention.

The apparatus illustrated in the present application is intended for use with car retarder actuating mechanism of the kind shown in Letters Patent of the United States, No. 1,605,044, granted to L. V. Lewis on November 2, 1926. In the present application, 20 the reference character D designates the controlling magnet of the admission valve D shown in the said Letters Patent. The reference character E designates the controlling magnet of the exhaust valve E in the Lewis patent, and the reference character F designates the controlling magnet of the restoring valve F in the Lewis patent. The circuit controllers K²⁰, K⁴⁰, and K⁶⁰, are responsive to the pressure in the application end of the 30 fluid pressure motor M in the Lewis patent and are arranged to open when the pressure in said motor exceeds 20 lbs. per square inch, 40 lbs. per square inch and 60 lbs. per square inch, respectively. The circuit controllers 35 L²⁰, L⁴⁰, and L⁶⁰ are likewise responsive to the pressure in the application end of the motor M and are arranged to open when the pressure exceeds 23 lbs. per square inch, 43 lbs. per square inch, and 63 lbs. per square 45 inch, respectively.

The retarder control valves D, E, and F, are controlled by a manually operable lever G having six positions. The first position is designated R, and is the position in which the lever is placed when it is desired to re-

store the car retarder to its normal or open position. The second position of the lever G is designated N and is the normal position, that is, the position in which it is placed when no operation of the retarder is desired. 55 The third position of the lever G is designated P²⁰, meaning that when the lever is in this position a pressure of 20 lbs. per square inch will be admitted to the application end of the car retarder operating motor. The 60 fourth and fifth positions of the lever G are respectively designated P⁴⁰ and P⁶⁰, meaning that when the lever is in position P⁴⁰ a pressure of 40 lbs. per square inch will be admitted to the operating motor, and when the lever is in the position P⁶⁰ a pressure of 60 lbs. per square inch will be admitted to the operating motor. The last position of the lever G is designated P⁸⁰; when the lever is 65 in this position the full available pressure 70 will be admitted to the operating motor, it being assumed that the full available pressure is 80 lbs. per square inch.

In Fig. 1, the lever G is connected with the retarder actuating apparatus by three line wires designated 1, 2, and 3, respectively. Associated with the retarder actuating apparatus are eleven asymmetric units designated U¹ to U¹¹, respectively, each of which units may be similar to those disclosed and claimed in Letters Patent of the United States, No. 1,640,335, granted to L. O. Grondahl August 23, 1927. 75

The operation of the apparatus shown in Fig. 1 is as follows: As shown in the drawing, the lever G is in the normal position, so that all circuits leading to the retarder actuating apparatus are open. I will first assume that the operator desires to apply a pressure of 20 lbs. per square inch to the retarder motor. To do this, he moves the lever G to position P²⁰, whereupon a circuit for the admission valve D becomes closed, which circuit is from the middle point 11 of battery A, through contact 7 of lever G, wire 14, line 80 wire 2, wires 15 and 16, asymmetric unit U⁶, circuit controller K⁴⁰, wire 17, admission valve magnet D, wires 18 and 19, unit U³, wires 20 and 21, circuit controller K²⁰, wire 22, unit U¹⁰, line wire 3, wires 23 and 24, con- 85

90 95 100

three, but that the required number of asymmetric units U is reduced.

As shown in the drawing, the lever G is in the normal position, with the result that all circuits are open. If the operator desires to apply a pressure of 20 lbs. per square inch to the retarder motor, he moves the lever G to position P²⁰, whereupon current flows from the middle terminal 11 of battery A, through wires 46 and 47, contact 10 of lever G, line wire 3^a, admission magnet D, wire 48, pressure responsive contact K²⁰, wire 49, pressure responsive contact K²⁰, wire 50, line wire 2, lever contact 5, and wire 51 to the negative terminal of battery 12. At the same time the exhaust magnet E is energized in multiple with magnet D, the circuit for magnet E passing from line wire 3^a, through magnet E, wire 52, contact L⁴³, wire 53, contact L²³ and wire 54 to line wire 2. When the pressure in the operating motor reaches 20 lbs. per square inch contact K²⁰ opens and so the admission of pressure ceases.

If the operator desires to build up the pressure in the retarder motor to 40 lbs. per square inch, he moves the lever G to position P⁴⁰ and current then flows from the middle terminal 11 of battery A, through wires 46 and 47, contact 10, wire 3^a, magnet D, wire 48, contact K⁴⁰, wire 55, line wire 1, and lever contact 4, to the negative terminal 12 of battery A. The exhaust magnet E is also energized in multiple with magnet D, the circuit for magnet E passing from line wire 3^a, through magnet E, wire 52, contact L⁴³, wires 56 and 57, and asymmetric unit U³ to line wire 1. The pressure in the retarder motor then builds up to 40 lbs. per square inch, at which point contact K⁴⁰ opens and so prevents further increase of pressure.

If the operator desires to increase the motor pressure to 60 lbs. per square inch, he moves the lever G to position P⁶⁰, thereby closing a circuit which passes from positive terminal 10 of battery A, through 58, lever contact 8, line wire 3, asymmetric unit U⁷, wire 57, asymmetric unit U⁸, wires 55 and 49, contact K⁶⁰, unit U², magnet D, line wire 3^a, lever contact 10 and wires 47 and 46 to the middle terminal 11 of battery A. The exhaust magnet E is energized in multiple with magnet D, the path for the exhaust magnet passing from asymmetric unit U⁷, through wires 56 and 53, contact L⁶³, unit U⁶ and magnet E to line wire 3^a. The motor pressure then builds up to 60 lbs. per square inch, at which point contact K⁶⁰ opens and thus prevents the further admission of air to the retarder motor.

In order to increase the pressure in the retarder motor to 80 lbs. per square inch, the operator moves lever G to position P⁸⁰, and current then flows from the positive terminal 10 of battery A, through wires 58, 59, and 60, lever contact 7, wires 61 and 62, line wire 2,

asymmetric units U¹ and U², admission magnet D, line wire 3^a, lever contact 10, and wires 47 and 46 to the middle terminal 11 of battery A. This circuit is provided with a multiple path including the exhaust magnet E, this path being from line wire 2, through wire 54, asymmetric units U⁵ and U⁶, and magnet E to line wire 3^a.

To reduce the pressure in the retarder motor from 80 lbs. to about 60 lbs., the operator returns lever G to position P⁶⁰, whereupon the circuit of exhaust magnet E includes contact L⁶³, so that when the pressure in the retarder motor is reduced to substantially 63 lbs. per square inch this contact closes, and the reduction of pressure ceases.

Similarly, to reduce the pressure to about 40 or 20 lbs. per square inch, the operator returns lever G to position P⁴⁰ or P²⁰, whereupon the circuit of exhaust magnet E includes contact L⁴³ or L²³, with the result that when approximately the desired pressure is reached one or the other of these contacts closes to prevent further reduction of pressure.

To restore the retarder to its full open or normal position, the operator moves lever G to position R, whereupon the restoring magnet F becomes energized, the circuit being from positive terminal 10 of battery A, through wires 58, 59, and 63, lever contact 6, wires 64 and 62, line wire 2, wire 65, restoring magnet F, asymmetric unit U⁴, line wire 3, wire 66, lever contact 9, and wires 67 and 46 to the middle terminal 11 of battery A. This admits pressure to the restoring end of the retarder motor, and after the retarder has been restored to its normal position the operator returns the lever G to its normal position.

It will be noted from the foregoing, that in each form of apparatus embodying my invention the pressure applied to the retarder motor will follow the position of the control lever, and that I have accomplished this without the use of a relay at the retarder and without the necessity for the operation of a push button in the control tower. Furthermore, by the use of the asymmetric units I am able to accomplish this result with a smaller number of line wires than have heretofore been necessary in the absence of the push button, and with apparatus shown in Fig. 1 I am able to accomplish the said result with one less line wire than has been necessary when a push button is used.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. Apparatus for controlling the supply of fluid pressure to a car retarder actuating motor, comprising an admission magnet, an exhaust magnet, a restoring magnet, a first series of contacts responsive to the pressure in the application end of said motor and arranged to open at progressively increasing pressure values, a second series of contacts responsive to the pressure in the application end of said motor and arranged to open at progressively increasing pressure values, each contact in the second series being arranged to open at a slightly higher pressure than the corresponding contact in the first series, a control lever, a plurality of asymmetric units, and circuits for said magnets including said pressure responsive contacts and said asymmetric units and contacts operated by said control lever.
2. Apparatus for controlling the supply of fluid pressure to a car retarder actuating motor, comprising an admission magnet, an exhaust magnet, a first series of contacts responsive to the pressure in the application end of said motor and arranged to open at progressively increasing pressure values, a second series of contacts responsive to the pressure in the application end of said motor and arranged to open at progressively increasing pressure values, each contact in the second series being arranged to open at a slightly higher pressure than the corresponding contact in the first series, a control lever, a plurality of asymmetric units, and circuits for said magnets including said pressure responsive contacts and said asymmetric units and contacts operated by said control lever.
3. Apparatus for controlling the application of fluid pressure to a car retarder actuating motor, comprising an admission magnet, a series of three contacts responsive to the pressure in the application end of said motor and arranged to open at progressively increasing pressure values, a first, a second, and a third conductor, a control circuit for said magnet including one of said contacts and the first and second conductors, a second control circuit for said magnet including another of said contacts and the second and third conductors, and a third control circuit for said magnet including the third contact and the first and third conductors.
4. Apparatus for controlling the application of fluid pressure to a car retarder actuating motor, comprising an admission magnet, a series of three contacts responsive to the pressure in the application end of said motor and arranged to open at progressively increasing pressure values, a first, a second, and a third conductor, a first, a second, and a third manually operable device, a control circuit for said magnet including the first and second conductors and controlled by one of said contacts and the first said manually operable device, a second control circuit for said magnet including the second and third conductors and controlled by another of said contacts and the second said device, and a third control circuit for said magnet including the first and third conductors and controlled by the third contact and the third said device.
5. Apparatus for controlling the supply of fluid pressure to a car retarder actuating motor, comprising an admission magnet, an exhaust magnet, a first series of contacts responsive to the pressure in the application end of said motor and arranged to open at progressively increasing pressure values, a second series of contacts responsive to the pressure in the application end of said motor and arranged to open at a slightly higher pressure than the corresponding contact in the first series, a control lever, a plurality of asymmetric units, a plurality of control circuits for said admission magnet each of which includes said admission magnet and a contact of the first series respectively as well as one of said asymmetric units, and a branch path for each of said control circuits passing around the admission magnet and the associated contact and including said exhaust magnet and the corresponding contact of the second series.

In testimony whereof I affix my signature.
